UNITED STATES PATENT OFFICE.

EDOUARD DION, OF LACHINE, QUEBEC, CANADA.

DOOR-OPENING AND CATTLE-RELEASING DEVICE.

Application filed September 15, 1923. Serial No. 662,927.

To all whom it may concern:

Be it known that I, EDOUARD DION, a subject of the King of Great Britain, residing at Lachine, in the Province of Quebec, Canada, have invented certain new and useful Improvements in Door-Opening and Cattle-Releasing Devices; and I do hereby declare that the following is a full, clear, and exact description of the invention, such 10 as will enable others skilled in the art to which it appertains to make and use the same.

The present invention pertains to a novel device for opening the doors of a barn in case of fire. The invention further includes 15 a mechanism for releasing the cattle from their stalls simultaneously with the opening of the doors.

With these objects in view the invention 20 comprises a weighted cable extending along the length of the barn at the interior thereof and having one or more fuses inserted therein. Within the barn is also supported a rotatable shaft connected to the weighted 25 cable in such a manner as to be turned when the weight drops as a result of the breaking of one of the fuses. The end walls of the barn are provided with fire doors normally pulled outwardly by means of springs but 30 ordinarily locked by means of latches. The above mentioned shaft carries several rocker arms which have link and bell crank connections to the latches. When the cable breaks, the shaft and rocker arms are 35 turned, causing the latches to be released and the doors to fly open.

The invention further includes a device 40 for releasing the cattle when the doors are opened. A number of tether poles are disposed within the stalls and are normally held in place by means of eyes. The above mentioned shaft is suitably connected to the tether poles to lift them out of the eyes when the shaft is turned in the manner 45 above described. As the poles are thus released, the cattle are free to withdraw therefrom and escape through the open doors.

The invention is fully disclosed in the following description and in the accompanying 50 drawings, in which:

Figure 1 is a transverse vertical section of a barn equipped with the invention, taken on the line 1-1 of Figure 7;

Figure 2 is a fragmentary elevation showing a door;

Figure 3 is a transverse vertical section on the line 3-3 of Figure 7;

Figure 4 is a transverse vertical section corresponding to Figure 3, and showing the weight lowered;

Figure 5 is a section on the line 5-5 of Figure 2;

Figure 6 is a section corresponding to Figure 5, showing the latch raised;

Figure 7 is a longitudinal vertical section 65 of the barn;

Figure 8 is a plan view of one of the series of stalls;

Figure 9 is a fragmentary horizontal section of one end of the barn;

Figure 10 is an end elevation of the stalls; and,

Figure 11 is a fragmentary perspective view of a stall partition and associated parts.

Reference will now be had to these views 75 by means of like characters which are employed to designate corresponding parts throughout.

Figures 1 and 7 show a barn comprising side walls 1 and 2, end walls 3 and 4 and a 80 roof 5. Each of the end walls is provided with a pair of fire doors 6 adapted to be held closed by means of pivoted latches 7 receivable in keepers 8 secured to the end walls. Adjacent the doors the end walls carry angular brackets 9 to which are attached springs 10 connected to the doors. By means of these devices the doors fly open when the latches are released. Each fire door contains a small door 11 to be used by a person entering and 90 leaving the barn.

At opposite sides of the longitudinal center of the barn are erected rows of stall partitions 12 forming two series of stalls 13. At the inner edge of each partition is secured a 95 bearing member 14, and a pair of parallel shafts 15 are supported in these bearings. From these shafts, arms 16 extend into the stalls and carry tether poles 17 slidable in eyes 18 also secured to the partitions. Each 100 pole is surrounded by a ring 19 to which is connected a chain 20 which may be attached to the body of the animal in any suitable manner.

An eye 21 is secured to one of the end walls at a point near the apex of the roof. The eye is engaged by a hook 22 to which is connected a fuse 23. The opposite end wall supports a pulley 24, and a cable 25 extends from the fuse 23 around the pulley. An- 110

other fuse 23' is interposed in the cable, and as many of these fuses as desired may be inserted.

The end walls also carry bearings 26 disposed vertically beneath the eye 21 and pulley 24. Within these bearings is journaled a shaft 27, to the ends of which are secured rocker arms 28, as clearly shown in Figure 3. The end walls further carry bearings 29 offset laterally with reference to the apex of the roof and disposed above the fire doors 6. In each of these bearings is journaled a bell-crank lever 30 connected to one end of a rocker arm 28 by means of a link 31. The shaft 27 also carries a finger 32 adjacent to one of the rocker arms 28. From this finger depends a cord 33 at the lower end of which is a ring 34. This ring receives the free end of the cable 25 as shown in Figures 1, 3 and 4. From the ring is suspended a weight 36 by means of a cord 35. To the remaining ends of the bell-crank levers 30 are attached rods 37 having hooked ends 38. These rods are guided in eyes 39 secured to the inner faces of the end walls, and the hooks are passed through openings 40 in the end walls to engage the lower edges of the latches 7.

In the operation of the device as thus far described, the fuses 23 and 23' will break when a predetermined temperature exists within the barn. As a consequence of the breaking of the cable, the weight 36 falls and causes the shaft 27 to turn. The turning of the shaft tilts the rocker arm 28 and pulls the links 31 inwardly. The bell crank levers 30 are turned on their pivots and raise the rods 37. The hooked ends 38 of the latter raise the latches 7 and allow the fire doors to be pulled open by the springs 10.

A pair of braces 41 spaced inwardly from the end walls carry bearings 42 to which are pivotally connected four bell crank levers 43 at opposite sides of the longitudinal center line, as illustrated in Figures 1, 7 and 10. In vertical alinement with these levers the shaft 27 carries a pair of shorter rocker arms 44. The ends of these two rocker arms are connected to the four bell-crank levers 43 by means of links 45. As will be seen from Figure 8, the ends of the shafts 15 are bent outwardly as at 46. The remaining ends of the bell crank levers 43 are connected to these bent ends by links 47 as shown in Figures 7 and 8.

When the shaft 27 is turned in the manner above described, the short rocker arms 44 are likewise tilted. This movement turns the bell crank levers 43 inwardly on their pivots whereby the links 47 are raised. The shafts 15 are consequently turned, lifting the arms 16 upwardly. As a result of the latter movement the tether poles 17 are withdrawn from the eyes 18, and the links 19 slip therefrom, releasing the animals. The

cattle are therefore free to escape from the barn as soon as the doors 6 are opened.

Along the apex of the roof is supported a water pipe 48 carrying the sprinkler heads 49. It will be apparent that the sprinkler pipe may be provided with a valve operable on the breaking of the cable 25, so that the water may be turned on as the interior of the barn reaches a sufficiently high temperature.

Although a specific embodiment of the invention has been illustrated and described, it will be understood that various changes in the details of construction may be made without departing from the scope of the invention as indicated by the appended claims.

Having thus fully described the invention, what I claim as new and desire to protect by Letters Patent is:

1. In combination with a barn having a plurality of fire doors, latches for said doors, a weighted cable, a shaft journaled in the walls of the barn, rocker arms secured to said shaft, a finger secured to the shaft and connected to the weighted cable, bell crank levers supported within the barn, link connections between the rocker arms and the bell crank levers, and hooked rods secured to said bell crank levers, said rods engaging the latches for releasing the latter.

2. In combination with a barn having a plurality of fire doors, a plurality of stall partitions within the barn, shafts extending along said partitions, arms extending from said shafts, and into the stalls, eyes secured to said partitions, tether poles connected to the arms and guided in said eyes, a weighted cable supported by the barn, fuses inserted in said cable, an additional shaft supported by the barn, and operative connections between the cable and said last named shaft and between the last named shaft and the first named shafts.

3. In combination with a barn having a plurality of fire doors, latches for said doors, a plurality of stall partitions disposed within the barn, a pair of shafts extending along said partitions, arms extending from said shafts into the stalls, eyes secured to said partitions, tether poles connected to said arms and guided in the eyes, a weighted cable supported by the barn, fuses inserted in said cable, a third shaft supported by the barn, rocker arms carried by said shaft, an operative connection between the cable and one of said rocker arms, connecting means extending from the rocker arms to the latches and from the rocker arms to the first named shafts.

4. In combination with a barn having a plurality of fire doors, latches for said doors, a plurality of stall partitions disposed within the barn, a pair of shafts extending along said partitions, arms extending from said shafts into the stalls, eyes secured to said partitions, tether poles connected to said

arms and guided in the eyes, a weighted cable supported by the barn, fuses inserted in said cable, a third shaft supported by the barn, rocker arms carried by said shaft,
5 an operative connection between the cable and one of said rocker arms, connecting means extending from the rocker arms to the latches, and from the rocker arms to the

first named shafts, and springs secured to the outer faces of the end walls and to the 10 doors for opening the latter when the latches are released.

In witness whereof I have hereunto set my hand.

EDOUARD DION.
